UNITED STATES PATENT OFFICE.

AUGUSTUS J. TOMBRINCK, OF SOUTH OMAHA, NEBRASKA.

LIFTING-JACK.

1,122,336.

Specification of Letters Patent. Patented Dec. 29, 1914.

Application filed April 6, 1914. Serial No. 829,810.

To all whom it may concern:

Be it known that I, AUGUSTUS J. TOMBRINCK, a citizen of the United States, residing at South Omaha, in the county of Douglas and State of Nebraska, have invented 5 certain new and useful Improvements in Lifting-Jacks, of which the following is a specification.

This invention relates to an improvement 10 in lifting jacks, and has for its principal object to provide such a construction that the parts may be quickly adjusted to the required height for engagement of the jack or bracket with the object to be lifted or lowered, another object being to provide a 15 mounting for the hand lever outwardly of and free from the bracket, in order that it may be conveniently detached, this being an advantage since, after it is detached, it will 20 not be obtrusive when the device is packed in a tool-box.

Another object of the invention is to provide such a mounting for the lever that the screw of the lifting jack may be rotated in 25 either direction by swinging the lever in a limited arc, this being of advantage in many instances during operation.

With these and other objects in view, as hereinafter mentioned, the invention presents 30 a novel construction, combination and arrangement of parts as described and claimed, and as illustrated in the drawing, wherein,

Figure 1 is a plan view of a lifting jack 35 embodying the invention, a part of the base being broken away. Fig. 2 is a view of the same in side elevation. Fig. 3 is a view of the lifting jack in longitudinal section, a part of the lever and lever-platform being 40 removed. Figs. 4 and 5 are plan views showing modified forms for the lever.

Referring now to the drawing for a more particular description, numeral 6 indicates the screw of the lifting jack, said screw having any suitable length and diameter, and 45 provided with a base 7.

At 8 is indicated a sleeve formed with a boss *a* at its lower end and provided with exterior threads *b* intermediate the boss and 50 its free end; and as indicated at *c* in Fig. 3, the sleeve is interiorly threaded near its lower end, so that, comparatively, a less degree of friction will be produced when it is rotated.

At 9 is indicated a bracket consisting of a sleeve *d* and ledge or shelf *e* preferably hav-

ing a rugose, upper surface, as shown. The sleeve is interiorly threaded for engagement with the threads *b* of sleeve 8. As thus described, sleeve 8, when rotated, may have a 80 movement longitudinally of and nearly the entire length of the screw 6 for elevating objects to a considerable height, the bracket 9 remaining stationary with respect to sleeve 8 during such operation, and it will be seen 85 that the construction provides means for convenient adjustments since the bracket may be disposed upon sleeve 8 at any desired part of its length. Sleeve 8 is provided with a groove 10 extending longitudinally thereof; 70 and slidably mounted on this sleeve outwardly of the bracket is a toothed collar or ratchet wheel 11, provided with an inwardly-projecting lug *f* for engaging in said groove. As best shown in Fig. 3, the ratchet wheel is 75 provided with an annular recess or groove *g* to provide a mounting for the circular rim *h* of the platform 12, whereby the platform is maintained substantially at right angles to the longitudinal axis of the ratchet wheel. 80

The platform, near its outer end, is provided with a pivot-pin 13 upon which is mounted a hand lever 14 provided at its inner end with oppositely-disposed projections 15 and 16. Lever 14 is also provided, 85 inwardly of its pivotal mounting, with an elongated aperture 17 formed transversely therein and traversed by the pin or keeper 18 which is mounted in said platform, adjacent to rim *h*. As thus described the lever 90 may have a limited swinging movement, horizontally, in either direction, with reference to the platform, these movements being limited by the contact of the projections with the ratchet wheel, the head of pin 18 95 tending to hold the inner end of the lever upon the platform. An operator may swing the lever in such a manner that the projection 15 will engage the teeth of the ratchet wheel, and a further swinging movement of 100 the lever in the same direction will cause a rotatable movement of sleeve 8 for elevating the sleeve and the bracket, for the reason that the ratchet wheel is splined on said sleeve; and this operation may be continued, if desired, until sleeve 8 has moved upward to dispose its threaded part *c* in engagement with the uppermost threads of screw 6.

To lower sleeve 8, the operator swings the hand lever in an opposite direction with reference to the platform until projection 16 110 engages the ratchet wheel, and by a further

movement of the lever in the same direction, a rotatable movement will be imparted to sleeve 8 to cause it to be lowered, and since the bracket remains stationary with the sleeve at this time, said bracket will also be lowered; and the operation may be continued, if desired, until the lower end of sleeve 8 engages the base 7.

It will be understood that lever 14 swings with practically no resistance in one direction, the projections of the lever being disengaged from the teeth, the rim *h* of the platform sliding circularly in the groove *g* of the ratchet wheel; but swinging movements of the lever in the opposite direction are attended with resistance since one of the projections is engaged by the ratchet wheel which rotates sleeve 8.

While the lever 14 shown in Figs. 1 and 20 2, is the preferred construction, other levers could be substituted therefor, and I may employ the lever 14' shown in Fig. 4 or the lever 14'' shown in Fig. 5. Lever 14' is provided with elongated apertures 19 and 25 20 formed longitudinally thereof, recesses 21 being formed in the lever at right angles to and opening on the ends of aperture 20. By this construction, said lever 14' may be substituted for lever 14, and may have slideable movements on the platform 12, the pins 30 13 and 18 respectively engaging in apertures 19 and 20 of said lever 14'; and when the parts are thus disposed, by manipulation of lever 14', in the manner already described, 35 the projections 15' and 16' may engage the teeth of the ratchet wheel for rotating said

wheel and sleeve 8. Fig. 5 shows a lever 14'' provided with a curved slot or aperture 22 within which pin 13 may engage, and the lever may be moved upon the platform 12 to 40 cause its respective projections 15'' and 16'' to engage the teeth of the ratchet wheel, for the same purpose.

It will be noted that the screw and sleeve provide for unusual longitudinal extension 45 so that objects may be elevated, comparatively, a considerable height. The lever, when disposed horizontally, is operative in a variety of positions, and may operate in a limited arc for rotating the sleeve; and since 50 the device consists of few and simple parts it may be manufactured economically, and will be durable in wear.

Having described construction in detail, a further explanation relating to operation 55 is not necessary.

What I claim and desire to secure by Letters Patent is,—

A lifting jack comprising a screw, a sleeve threaded thereon, a bracket threaded on the 60 sleeve, an annular member splined on the sleeve and disposed outwardly of the bracket, and means to rotate said annular member to cause a rotatable movement of the sleeve for adjusting said sleeve longitudinally of the screw.

In testimony whereof, I have affixed my signature in presence of two witnesses.

AUGUSTUS J. TOMBRINCK.
